Inventor
William M. Cummiskey.
By his Attorney
E. M. Marshall

UNITED STATES PATENT OFFICE.

WILLIAM M. CUMMISKEY, OF NEWARK, NEW JERSEY.

TIMER.

Application filed September 24, 1919. Serial No. 326,011.

To all whom it may concern:

Be it known that I, WILLIAM M. CUMMISKEY, a citizen of the United States of America, and a resident of Newark, Essex County, State of New Jersey, have invented certain new and useful Improvements in Timers, of which the following is a specification, reference being had to the accompanying drawings, forming a part thereof.

10 My present invention relates to a timer for internal combustion engines.

15 The objects of the invention are to provide a timer of simple practical construction in which friction and wearing of the parts will be reduced to a minimum and in which the circuit connections will be accurately controlled without burning or pitting of the contacts or terminals.

20 These objects I have accomplished in part by the provision of a timer arm in the form of an annular ball bearing having the inner race ring thereof eccentrically engaged on the timer shaft and the outer race ring thereof arranged to actuate or control the 25 circuit connections.

The foregoing and other features of the invention will be described more fully as the specification proceeds.

20 In the drawings accompanying the specification, Figure 1 is an end or plan view of a timer embodying my invention, said view being taken substantially on the plane of the line 1—1 of Figure 2, and thus showing the cap or housing and certain other parts 35 of the timer in section.

Figure 2 is a centrally sectional view taken substantially on the plane of the line 2—2 of Figure 1.

40 Figure 3 is a detail view of a modification.

5 designates the timer shaft and 6 the cap or cover of the timer housing, said cover being usually constructed of insulating material and shown as mounted on the metallic 45 base plate 7 which, insulated for the purpose of spark adjustment is rotatably supported at 8 and is suitably shifted by means of the connection 9.

50 The timer illustrated is intended for a 4-cylinder engine and is therefore provided with four contacts or terminals denoted by 1, 3, 4 and 2, with which cooperate relatively movable grounded contacts 10, 11, 12 and 13 respectively. These movable contacts are 65 carried by spring arms arranged in pairs. Thus the support for the contacts 10 and 13

consists of a V-shaped spring 14 supported at its apex and carrying the contacts 10 and 13 on the outward or free ends of the divergent spring arms thereof and the support 60 for the contacts 11 and 12 consists of a similar V-shaped spring 15 carrying the contacts 11 and 12 at the free ends thereof. These springs are shown as fastened at the bend thereof to metallic bushings 16 pivotally engaged on the metallic supporting posts on the plate 7 which is grounded to the engine frame 17.

The contact actuating arm comprises in the present disclosure a ball bearing of the 70 annular type embodying an inner race ring 18 fixed eccentrically on the timer shaft, and an outer race ring 19 with the roller elements or balls 20 interposed therebetween. The outer race ring engages in between the 75 arms of the V-shaped springs and the inner race ring is eccentrically mounted on the shaft in the illustration by means of an eccentric insulating bushing 21 to which the inner race is keyed as indicated at 22, and 80 which is fastened to the shaft as by means of a set screw 23.

It will be evident that in the eccentric rotation of the inner race ring, the outer ring will be forced outwardly and will in turn 85 force the movable contacts sequentially into engagement with the terminals provided therefor, thus establishing the various circuits in the proper order and practically without any wear or friction on any of the 90 parts. It will be noted also that in the flexing of the spring arms, the movable contacts will have a certain wiping movement over the relatively stationary contacts. This tends to keep the contact faces bright and 95 clean at all times and to prevent pitting and carbonizing. The device it will be seen is relatively simple and inexpensive and may be so designed as to fit on standard cars in use at the present time.

100 The form of the invention disclosed in Figure 3 is adapted to be used as a substitute for the rotating distributor arms now widely used in ignition systems of the so-called battery distributor types, the same 105 differing from the form first disclosed, principally in that there is no actual engagement of the contacts, the current being obliged to jump a short gap across the terminals as they are brought into register. These 110 outer distributor terminals are designated 1, 2, 3 and 4, as before, but in this case, the

inner cooperating terminals are in the form of points or protuberances 10^A, 11^A, 12^A, 13^A, carried by the outer race ring and the outer race ring is held against rotation, as by means of the flexible finger 25. The operation will be obvious, it being apparent that as the eccentric inner ring is rotated the outer ring will be oscillated so as to bring the points carried thereby sequentially into current transmitting relation to the surrounding relatively stationary terminal points. This construction has an important advantage over the usual distributor arm in that the current instead of all being carried by one arm is distributed over the four sets of points.

What I claim is:

1. In a timer, the combination of a timer shaft, an insulating bushing eccentrically mounted on the timer shaft, an inner race ring fixed to said bushing, an outer race ring surrounding the ring, roller elements between the race rings and contact controlling terminals disposed about the outer race ring and spring pressed contact arms engaged by said outer race ring.
2. In a timer, a combination of a timer shaft, contacts disposed about said shaft, diverging spring pressed contact arms provided with contacts for engagement with the first mentioned contacts, and an annular ball bearing having an inner race ring eccentrically mounted on the timer shaft but insulated therefrom and having an outer race ring arranged to engage at all times with the contact arms aforesaid.
3. In a timer, the combination of a timer shaft and contacts disposed about the same, an insulating bushing eccentrically mounted upon the timer shaft, an annular ball bearing having the inner race ring thereof engaged on said insulating bushing and diverging contact arms engaged with the outer race ring of the bearing and pro-
- vided with contacts for engagement with the contacts aforesaid.
4. In combination with a timer shaft and spaced terminals disposed at opposite sides of the same, a substantially V-shaped spring supported at the apex thereof and having its arms extending to points opposite the terminals, and an annular ball bearing having the inner race ring thereof eccentrically engaged on the timer shaft and the outer race ring thereof interposed between the arms of the V-shaped spring.
5. In a timer, a timer shaft, terminals disposed at opposite sides of the same, a post mounted intermediate said terminals, a bushing engaged on said post, a substantially V-shaped spring having the apex portion thereof secured to said bushing and the arms thereof extended into position opposite the terminals, and an annular ball bearing having the inner race ring thereof eccentrically engaged on the timer shaft and the outer race ring thereof interposed between the arms of the V-shaped spring.
6. In combination, a timer shaft, an annular ball bearing having the inner race ring thereof eccentrically engaged on said shaft, substantially V-shaped springs supported at their apexes and having divergent arms thereof engaging the outer race ring of the bearing and relatively stationary terminals disposed substantially opposite the outer free ends of the substantially V-shaped springs.
7. In combination, a timer shaft, an inner bearing ring eccentrically mounted on said timer shaft, an outer bearing ring surrounding said inner bearing ring, and a plurality of pairs of circuit controlling arms engaging said outer bearing ring, each pair of arms being mounted on a common pivot.

In witness whereof, I hereunto set my hand this 23rd day of September 1919.

WILLIAM M. CUMMISKEY.
